2,611,503

FILLER CAP FOR GASOLINE TANKS

Owen H. Griswold, Ridgewood, N. J.

Application February 18, 1949, Serial No. 77,239

13 Claims. (Cl. 220—25)

1

This invention relates, as indicated to a filler cap for fuel, oil, ethylene glycol and water alcohol tanks of all sizes and types, but has reference more particularly to a cap designed especially for use in connection with standard fittings for filler cap attachment to self-sealing and conventional tanks of both military and commercial aircraft.

A primary object of the invention is to provide a filler cap of the character described, which will not leak under various test pressures or under the higher hydraulic ram pressures resulting from gun fire into the fuel tanks of aircraft, as prescribed by the Air Forces of the United States.

Another object of the invention is to provide a cap of the character described, the operation of which presents the least possible chance for "human error."

Another object of the invention is to provide a cap of the character described, which, after installation, cannot be misplaced.

A further object of the invention is to provide a cap of the character described, which can be quickly and easily secured or released.

A further object of the invention is to provide a cap of the character described, which, when used on pressurized fuel tanks, cannot blow off and thereby cause damage to material and personnel.

Other objects of the invention are to provide a cap which can be used to replace previous designs, now in service, without alterations to surrounding structures, to provide a cap which compensates for dimension changes in the rubber seal, due to aromatic and other fuels and to temperature changes, and to provide a cap which is lighter in weight than the standard designs now in use.

Other objects and advantages of the invention will be apparent during the course of the following description.

In the accompanying drawings, forming a part of this specification, and in which like numerals are employed to designate like parts throughout the same,

Fig. 1 is a fragmentary cross-sectional view of a typical or conventional airplane wing; showing a fuel tank provided with the tank filler cap of the present invention;

Fig. 2 is a top plan view of the tank filler cap;

Fig. 3 is a fragmentary view, partly in elevation and partly in section, taken on the line 3—3 of Fig. 2;

Fig. 4 is a cross-sectional view of the filler cap, taken on the line 4—4 of Fig. 5;

Fig. 5 is a cross-sectional view, taken on the line 5—5 of Fig. 4;

2

Fig. 6 is a view showing the position of the cap, when fully open;

Fig. 7 is a view similar to Fig. 6, but of the reverse side of the cap;

Fig. 8 is a perspective view of the slider assembly of the filler cap;

Fig. 9 is a bottom plan view of a portion of the adaptor, and

Fig. 10 is a transverse cross-sectional view of the adaptor, showing one of the cam slots.

Referring more particularly to the drawings, reference numeral 1 designates a fuel tank in an airplane, the upper wall of which is disposed below the skin S of the airplane. This cell or tank has a filler opening defined by an annular fitting 2, which is secured to the tank in the manner shown in Fig. 3, this fitting, which is part of the tank, being one of the type known as AN 4130-7 (Air Force—Navy Aeronautical Standards), or a similar fitting. Access to the filler cap, in this case, may be had through an access door (not shown), provided in the skin S, directly above the filler cap, or, the cap can be mounted flush with the skin contour.

25 Secured to the upper surface of the fitting 2, as by screws or bolts 3, is a filler cap, comprising an adaptor 4 in the form of a metallic disc having an annular outer edge 5 and an annular inner edge 6, in eccentric relation to the outer edge.

30 The adaptor has a flange 7 which extends downwardly into the filler opening defined by the fitting 2, the inner edge of this flange forming an opening 8 which is a continuation of the inner edge 6 of the adaptor. The flange 7 varies in thickness, as shown in Fig. 9, from a minimum at the point A, to a maximum at the points B, which are slightly more than 90 degrees from the point A, and rearwardly of the points B the flange decreases in thickness, and is provided

35 with a pair of spaced parallel ears or lugs 9. The ears 9 extend somewhat below the lower edge of the flange 7, and serve a purpose to be presently described.

40 The flange 7 is provided at diametrically opposite points adjacent the points B, with cam slots or grooves which communicate with the opening 8 defined by the flange, and have vertical portions 10 and inclined portions 11 extending from the upper ends of the portions 10.

45 A portion of the upper face of the adaptor 4 is removed to provide a seat or ledge 14 for a handle 15, which, when seated, has its upper surface substantially flush with the upper surface of the adaptor. The adaptor is further formed with a beveled surface 16 which forms a finger-hole for

lifting the handle 15, when the filler cap is to be opened.

The handle 15 is in the form of a segment of a disc, which, in seated or closed position, covers a portion of the opening 8 in the adaptor, and is provided with a stem 17 extending from the chordal edge of the handle, the upper surface of this stem being flush with that of the handle. Extending downwardly from the stem 17 of the handle is a pair of parallel spaced ears 18, having openings 19 therein for the reception of a pivot pin 20, the ends of which are mounted in a pair of spaced guides 21.

The guides 21 are also in the form of segments of discs, the chordal edges of which extend at right angles to the chordal edge of the handle 15. The upper surfaces of these guides, when in closed position, cover those portions of the opening 8 in the adaptor which are not closed by the handle 15 and stem 17 of the handle. Portions of the guides are cut away, as at 22, for the reception or seating of the handle 15, when the latter is in closed position.

The ears 18 are also provided with openings 23, which are spaced both longitudinally and vertically from the openings 19, and have mounted therein a pin 24, to which a slider assembly, generally designated by reference numeral 25, is pivotally secured. This slider assembly comprises a link 26, one end of which is connected to the pin 24, and the other end 27 of which extends angularly to the remainder of the link, and is connected, as by a rivet 28, to a slider 29 and a slider dog 30, the slider dog and slider being also connected to each other, as by a rivet 31. The slider dog has ends 32 which are bent angularly to the plane of the dog, these ends being normally disposed in the cam slots 11.

The slider 29 is normally disposed in a slot or groove 33 which extends diametrically across the upper face of a circular base member 34. The base member 34 has a lower surface, the central portion 35 of which is flat and parallel with the upper surface of the base member, and the outer portion 36 of which is conical. Extending downwardly from the flat surface 35 is an elongated tenon 37, which extends in a direction at substantially right angles to the long dimension of the slot or groove 33.

The guides 21 are secured to the base member 34 by means of rivets 38. A rubber seal 39, of a contour similar to that of the outer surface of the flange 7 of the adaptor, is secured to the lower surface of the base member 34, with the tenon 37 of the base member extending through a similarly shaped opening 40 in the center of the seal. The seal is secured to the base member in the following manner. A pressure plate 41 is provided, having a peripheral flange 42 in contact with the lower surface of the seal, adjacent the periphery thereof, the contour of the outer edge of this flange is substantially the same as that of the periphery of the seal. This pressure plate is secured in contact with the seal by means of two screws 43 which extend through an elongated slot 44 in the pressure plate and into tapped openings in the tenon 37. The heads of these screws bear against a hinge 45, which is disposed below the pressure plate, in spaced relation to the latter, and a leaf spring 46 is interposed between the upper surface of this hinge and the lower surface of the pressure plate. A seal clamping plate 47 bears against the lower surface of the seal, and is retained in clamping position by means of cylindrical spacers 48, which extend

through the slot 44 in the pressure plate, and are interposed between the clamping plate and hinge 45.

The hinge 45 is pivotally connected to a hinge pin 49, which is mounted in the ears 9 of the adaptor.

It will be noted that the rivet 28 has an elongated head 50, the lower end of which bears against the slider dog 30, and the other end of which is upset to provide a flange 51. The end 27 of the link 26 is connected to the head 50 of the rivet and has limited movement along this head, between the slider dog and the flange 51, the connection being, in effect, a lost-motion connection.

The screws 43 are locked against rotation, by means of a wire 52 which interconnects the heads of the screws.

There is also provided a locking spring 53, which interconnects bosses 54 which project downwardly from the guides 21. This spring is arcuate in form, to conform with the arcuate outer edges of the guides 21, and has inturned ends 55, which embrace the bosses 54 of the guides.

It will be noted that the screws 43 exert pressure on the hinge 45, spacers 48 and clamping plate 47. This leaves the peripheral portion of the seal 39 with a limited degree of flexibility relative to the conical portion surface 36 of the base member 34, there being a clearance of approximately 0.03 inch between the seal and the periphery of the surface 36. The rubber seal 39 is a synthetic of the Buna N class, and of all the types of rubbers, it is the one least affected by contact with aromatic fuels, while still retaining the desired mechanical properties. The Government specification for this rubber permits a volumetric increase or "swell" of 50% when in contact with aromatic fuel and it is therefore necessary to allow space for this expansion while maintaining pressure on the rubber to hold the seal. This accounts for the necessity of having the spring 46 apply force through the "floating" pressure plate 42 to maintain pressure between the seal 39 and the adaptor flange 7. The elasticity of the rubber cannot be relied upon to maintain pressure under conditions of -75° F. and the action of aromatic fuels. In addition, under production conditions, it is possible that the bottom 35 of the base member 34 may be above or below the sealing surface of flange 7. If it were below, the rubber seal 39 would be held away from flange 7, thus breaking the seal. To prevent this, the surface 36 has been made conical, with the clearance of 0.03" at its edge, which permits the plate 42 to press the peripheral portion of the seal 39 against flange 7 while holding it rigidly at its center under the clamping plate 47. Thus, the seal would assume a concave shape, due to its flexibility, and thereby maintain the sealing contact. When the tank contains pressure and the cap is opened, the seal assumes the above conical shape up to the .03", but as the cap is forced down more than .03", the outer edge of base 34 makes contact with rubber seal 39 and additional downward travel forces it away from flange 7. Due to the use of the internal (tank) pressure to aid rather than oppose the sealing, it is necessary to use the mechanical advantage of the mechanism to supply the necessary force.

The spring 46 is also positioned by contact of the spacers 48 with diametrically opposite points or crotches in the spring 46. While neither plate 41, nor spring 46 are restrained axially, they are

limited in their axial travel in one direction by means of the hinge 45, and in the opposite direction, they exert pressure on the peripheral portion of the seal.

The operation of the cap may be briefly described, as follows:

Assuming that the cap is in closed position, as shown in Figs. 2, 3, 4 and 5, the operation is as follows: The handle 15 is lifted by inserting the finger into the finger-hole 16, and by using the finger under the handle which has been thus initially lifted. To facilitate insertion of the finger under the handle, the handle is provided on its underface with a beveled surface 56, which is disposed adjacent the surface 16. As the handle is thus lifted, the pin 24 is caused to rotate about the pin 20, causing the slider assembly to be drawn toward the pin 20. This, in turn, causes the ends 32 of the slider dog to be moved along the inclined portions 10 of the cam slots in the adaptor, thereby forcing the cap downwardly relatively to the adaptor and forcing the seal 39 out of engagement with its seat on the adaptor, that is to say, out of engagement with the lower end of the flange 7. This is possible because the flexibility of the seal is limited, as above stated, to approximately 0.03 inch before coming into contact with the periphery of the base member 34, while the vertical movement of the cap, due to the inclination of the cam slots in the adaptor, is approximately 0.19 inch.

After the handle has been rotated through an angle of from 80 to 100 degrees relatively to the adaptor, the ends 32 of the slider dog are disposed above the vertical portions 10 of the cam slots, permitting the cap assembly to fall, by gravity, inwardly, the cap assembly pivoting about the hinge pin 49. As the cap assembly falls, it assumes a vertical position relatively to the adaptor, as viewed in broken lines in Fig. 3, and in Figs. 6 and 7, due to rotation of the cap assembly relatively to the handle 15 about the pin 24. In this way, the handle 15 above the adaptor is at an angle of approximately 90 degrees to the plane of the adaptor (or skin covering), and serves as a warning that the cap is open. Since the major dimension of the handle is a chord of the circular opening in the adaptor, which opening, in the usual case, is about 3 inches in diameter, the handle, in the open position, offers a minimum restriction, from the aerodynamical standpoint.

The cap is closed by pulling the handle 15 upwardly, until the ends 32 of the slider dog enter the vertical portions 10 of the cam slots in the adaptor, and then pushing the handle forwardly until the handle is flush with the adaptor and cap assembly. As the handle is thus being moved to closed position, the curved end of the slider 29 comes into contact with the center of the spring 53. Due to the relative positions of pins 20 and 24 and the point of contact of the link 26 with the rivet head 51, the pressure of the spring 53 on the slider assembly 25 tends to rotate the handle 15 in a clockwise direction, as viewed in Fig. 4, thereby holding the handle against the shoulders 22 of the guides 21. This is necessary to counteract the tendency of vibration and other accelerative forces to open the cap.

It is thus seen that I have provided a filler cap for fuel tanks, which has a number of distinct advantages over filler caps heretofore available.

(a) The cap will not leak under test pressures of 100 pounds per square inch, and under

the higher hydraulic ram pressures resulting from gun fire into the tank, as required by the Air Forces of the United States of America. This results from the fact that these pressures are utilized to force a seal against its seat, rather than away from the seat, as in previous designs.

(b) The cap presents the least possible chance of "human error" in its operation. With previous designs, it was possible to install the cap with only one side of the cross bar under its cam or dog, and it was also possible to rotate the cap through an angle less than sufficient to lock it, and in either case, vibration could cause the cap to be lost. Under both of these conditions, the cap was flush with the skin covering of the airplane, and appeared to be in position. There are several cases on record in which this has caused the loss of an airplane by fire. The cap of the present invention must be locked, or the cap and handle will not be flush with the skin covering, so that the locked condition is readily apparent, eliminating even a remote possibility of "human error."

(c) The cap cannot be misplaced. In previous designs, the cap has been held in place by a chain extending from the cap through the filler opening and attached to the "adaptor" or seat internally. These, in general, have proved unsatisfactory.

(d) The cap is quickly and easily secured or released. The hinge design of the mechanism guides the cap into the adaptor, making it unnecessary to feel for the cam openings, as in previous designs. Moreover, the lever action makes for easier application of forces for opening and closing, than the torque or twisting action required in previous designs.

(e) The cap, when used on pressurized tanks, cannot blow off, when released, and thereby cause damage to material and personnel. In some previous designs, the cap cannot be opened against pressure, because of jamming, whereas, in the present cap, the mechanical advantage of the lever and slope of the cam slots in the adaptor is utilized to accomplish this in an easy and positive manner.

(f) The cap can be used to replace previous designs, now in service, without alterations to surrounding structure.

(g) The cap compensates for dimension changes in the rubber seal, due to aromatic and other fuels, and to temperature changes.

(h) The cap is lighter in weight than the standard designs now in use.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a filler cap for fuel receptacles, an adaptor having a filler opening, a closure for said opening, said closure being pivotally secured to said adaptor, and a closure operator, said closure operator including a handle, a member pivotally secured to said handle, and a slider having a lost-motion connection with said member and slidably transversely of said closure, and means in said adaptor connected to said slider for camming said closure to closed position.

2. In a filler cap for fuel receptacles, an adaptor having a filler opening, a closure for said opening, said closure being pivotally secured to

said adaptor, guides connected to said closure and movable therewith, said guides defining a track therebetween, a closure operator comprising a handle pivotally secured to said guides and a slide member operatively connected to said handle, said slide member being slidable in said track.

3. In a filler cap for fuel receptacles, an adaptor having a filler opening and cam slots in the wall of said opening, a closure for said opening, said closure being pivotally secured to said adaptor, guides connected to said closure and movable therewith, said guides defining a track therebetween, a closure operator comprising a handle pivotally secured to said guides, and a slide assembly operatively connected to said handle, said guide assembly including a member slidable in said track, and a member having end portions movable in said cam slots.

4. A filler cap, as defined in claim 3, in which said handle is so shaped that, in association with said guides, it forms a secondary closure for said opening, said handle having a width greater than the diameter of said filler opening, whereby said handle is precluded at all times from falling through said opening.

5. A filler cap, as defined in claim 4, in which said slide assembly is pivotally connected to said handle.

6. In a filler cap for fuel tanks, a member having a filler opening and a downwardly facing seating surface, a closure pivotally connected to said member and including means for seating against said surface, said closure, when in its fully open position, being disposed in a plane substantially perpendicular to the plane of said member and below the plane of said seating surface, and means for moving said closure from said fully open position to a closed position in which said seating means is in contact with said surface, said means including a rigid handle operatively connected to said closure and movable in its entirety in an arc normal to the plane of said member during said closure-closing operation, said handle being entirely free of any connection to said member and being of a width greater than the diameter of said filler opening, whereby it rests on the upper edge of said member when the closure is in fully open position and cannot fall through said opening.

7. A filler cap, as defined in claim 6, in which said member has cam slots therein, and said closure moving means is provided with elements movable in said cam slots during movement of the closure between said positions.

8. A filler cap, as defined in claim 7, in which said cam slots have vertical and inclined portions, said vertical portions permitting the closure to fall by gravity when said elements are disposed therein.

9. In a filler cap for fuel receptacles, an adaptor having a filler opening, a closure pivotally connected to said adaptor and having sealing means

adapted to be moved into sealing contact with said adaptor, said closure, when in fully open position, being disposed in a plane substantially perpendicular to the plane of said adaptor, and means for moving said closure from said fully open position to a closed position in which said sealing means is in contact with said adaptor, said means including a handle supported by said adaptor, operatively connected to said closure and movable in an arc normal to the plane of said adaptor during said closure-closing operation, said connection including an element slidable transversely of said closure relatively to said closure during said movement.

10. A filler cap, as defined in claim 9, in which said adaptor has cam slots therein, and said closure operating means has elements movable in said cam slots during said movement.

11. A filler cap, as defined in claim 10, in which said transversely slidable element includes a slider dog having ends movable in said cam slots.

12. A filler cap, as defined in claim 11, in which said handle has a surface which lies substantially flush with the upper face of the adaptor when said closure is in closed position.

13. In a filler cap for fuel receptacles, an adaptor having a filler opening and a downwardly facing seating surface, a hinge pivotally connected to said adaptor, a closure carried by said hinge and comprising a rubber seal adapted to bear against said surface and close said opening, a pressure plate having a peripheral flange bearing against the peripheral portion of said seal, a resilient member carried by said hinge and interposed between said hinge and pressure plate, whereby said pressure plate is caused to bear resiliently against said rubber seal, and a base member carried by said hinge and having a central portion which bears against said rubber seal, and an outer or peripheral portion having a conical surface spaced from said rubber seal.
